UNITED STATES PATENT OFFICE

148,968

DESIGN FOR A COMBINED ARM REST AND DOOR PULL

Elmer G. Wettlaufer, Bloomfield Hills, Mich.

Application June 13, 1946, Serial No. 130,679

Term of patent 14 years

(Cl. D10—8)

To all whom it may concern:

Be it known, that I, Elmer G. Wettlaufer, a citizen of the United States, residing in Bloomfield Hills, in the county of Oakland and State of Michigan, have invented a new, original, and ornamental Design for a Combined Arm Rest and Door Pull, of which the following is a specification, reference being had to the accompanying drawing, forming a part thereof, wherein:

Figure 1 is a top plan view of a combined arm rest and door pull, showing my new design;

Figure 2 is a view in bottom plan of the device of Figure 1;

Figure 3 is a view in front elevation of the device of Figure 1; and,

Figure 4 is a view in end elevation of the device of Figure 1.

The dominant features of my design are shown in full lines.

I claim:

The ornamental design for a combined arm rest and door pull, substantially as shown and described.

ELMER G. WETTLAUFER.
